United States Patent Office

Des. 219,311
Patented Nov. 24, 1970

219,311

COPYMAKING MACHINE

Kenneth R. Reick, Oak Brook, Ill., assignor to Sunbeam
Business Equipment Co., Addison, Ill., a corporation
of Illinois

Filed Oct. 9, 1969, Ser. No. 19,488

Term of patent 14 years

Int. Cl. D16—05

U.S. Cl. D61—1

FIG. 1 is a perspective view of the machine showing the left side thereof and the right side is the same in mirror image;

FIG. 2 is a rear end elevational view of the machine; and

FIG. 3 is a top plan view of the machine.

I claim:

The ornamental design for a copymaking machine, as shown.
